UNITED STATES PATENT OFFICE.

HELEN A. RUSSELL, OF BROOKLYN, NEW YORK.

GAME-COUNTER.

SPECIFICATION forming part of Letters Patent No. 278,747, dated June 5, 1883.

Application filed October 23, 1882. (No model.)

To all whom it may concern:

Be it known that I, HELEN A. RUSSELL, of Brooklyn, Kings county, New York, have invented a certain Improvement in Game-Counters, of which the following is a specification.

It is the object of my invention to provide, in compact form, counting mechanism for keeping records relating to two or more different subjects.

10 In carrying out my invention I arrange around the outer part of a stationary disk any desired number of figures or diagrams representing serial numbers. In the center of the stationary disk I arrange a smaller disk, which is capable of being rotated, and which has a pointer projecting radially outward from its periphery. Beneath the stationary disk I provide a loose ring or perforated plate, having upon its outer edge a radial projection upon 15 which I mount another pointer, which is directed inward toward the center of the stationary disk. By means of these two pointers, which are capable of independent rotation and adjustment, the same circle of serial numbers may be used for registering two different 20 subject-matters. For example, the exterior pointer can be used to indicate the number of points made in a game of whist, and the interior one the number of games played, or vice 25 versa. I may also provide the rotating disk with a centrally-pivoted pointer for employment in connection with numbers or figures represented upon the face of the rotating disk.

The accompanying drawings, illustrating the 30 application of my invention in a game-counter, are as follows:

Figure 1 is a top view. Fig. 2 is a side elevation. Fig. 3 is a top view of the rotating disk with the pointer centrally pivoted thereon. 40 Fig. 4 is a side elevation of the rotating disk and centrally-pivoted pointer. Fig. 5 is a plan of the stationary disk upon which the serial numbers are arranged, and Fig. 6 is a side elevation thereof. Fig. 7 is a top view of the 45 loose ring which supports the exterior pointer. Fig. 8 is a side elevation of the ring and the base of the apparatus. Fig. 9 is a top view of the base with the other parts removed. Fig. 10 is a side elevation of the base, showing the

cylindrical boss which serves to centralize the 50 loose ring.

Referring to the drawings, the apparatus consists of the disk A, around the outer portion of which are symmetrically arranged a number of cards of the suit of diamonds, commencing with the ace, and indicating by the 55 number of spots upon them the serial numbers desired.

It will of course be understood that figures, numerals, or other diagrams answering the 60 purpose of representing serial numbers, may be employed instead of the representation of diamond-suit cards.

On the top of the disk A, I provide the small 65 rotating disk B, having the pointer B' projecting radially from its periphery.

The base of the apparatus is provided with the cylindrical boss C, to the top of which the disk A is fastened.

The ring D, by which the exterior pointer 70 D' is supported and carried, loosely incloses the cylindrical boss C, which centralizes the ring D, and makes the path of rotation of the exterior pointer D' concentric with the disk A.

A third pointer, E, may, if desired, be hung 75 upon the upper end of the pin F, which serves as the axis for the rotating disk B, in which case the face of the disk B may have figures or other devices represented upon it for use in connection with the pointer E. Thus, in the drawings the disk B is represented as having upon 80 its face representations of the four suits of cards, and the pointer may be employed in such case to indicate the trump-suit.

It will of course be seen that inasmuch as 85 the pointers B' and D' are wholly independent of each other, they can be separately used in connection with the single circle of figures upon the disk A to indicate two different numbers—as, for example, one may be used to indicate the number of games played, and the 90 other the number of points made.

The hub of the central pointer, E, is inclosed between the washers G and G', and it is intended that the frictional hold of the washer 95 G' upon the hub of the pointer and upon the disk B will be sufficient to cause the pointer E to be carried around when the disk B is ro-

tated, so that its position relatively to the figures or representations upon the face of the disk B will not be changed by the act of rotating that disk, but can be changed by rotating the pointer F without rotating the disk B.

5 I claim as my invention—

1. The improvement in game-counting apparatus herein-described, which consists of the following members, to wit: first, a stationary disk having displayed in a circle upon it a prescribed number of figures or diagrams representing serial numbers; second, a small rotating disk centrally pivoted upon the stationary disk, and provided with an outwardly-projecting pointer; and, third, a loose ring beneath the stationary disk, provided with a radial projection carrying another pointer di-

rected toward the center of the stationary disk, the whole mounted upon a suitable base, substantially as shown and described, and for the 20 purposes set forth.

2. In combination with the stationary disk A and the rotating pointers B' and D', the rotating disk B, with representations of card suits or other figures displayed upon its face, and the central pointer, E, adapted to be carried around when the disk B is rotated, but capable of being rotated independently of the disk B, the whole arranged substantially as shown and described.
